UNITED STATES PATENT OFFICE.

GEORGE A. MITCHELL, OF HUNTINGTON PARK, CALIFORNIA, ASSIGNEE TO MITCHELL
CAMERA CO., OF LOS ANGELES, CALIFORNIA, A CORPORATION OF CALIFORNIA.

KINETOGRAPH MOVEMENT.

1,403,880.

Specification of Letters Patent. Patented Jan. 10, 1922.

Application filed May 12, 1920. Serial No. 380,785.

To all whom it may concern:

Be it known that I, GEORGE A. MITCHELL, a citizen of the United States, residing at Huntington Park, in the county of Los Angeles, State of California, have invented new and useful Improvements in Kinetograph Movements, of which the following is a specification.

This invention has to do with a mechanical movement particularly adapted for use in kinetographs and the like; and an object of the invention is to provide a mechanism, for producing such a movement which is simple, compact and effective.

15 A feature of the invention is the construction and arrangement of the mechanisms and parts, employed to produce the desired movement, which make the machine particularly effective, smooth and even in operation, yet simple and compact.

20 There are many objects and features of the invention which will be best understood from the following specification of a preferred embodiment of the invention throughout which reference is had to the accompanying drawings in which—

25 Fig. 1 is a top plan, or elevation, of the mechanism provided by the invention; Fig. 2 is a bottom plan, or elevation, of the mechanism; Fig. 3 is a side elevation of the mechanism being a view taken as indicated by line 3—3 on Fig. 1; Fig. 4 is a rear view of the mechanism being a view taken as indicated by line 4—4 on Fig. 1; Fig. 5 is a detailed sectional view taken as indicated by line 5—5 on Fig. 3; Fig. 6 is a detailed sectional view taken as indicated by line 6—6 on Fig. 4 being a view showing the mechanism in its lowermost position, or after having moved the film downwardly; Fig. 7 is a detailed sectional view taken as indicated by line 7—7 on Fig. 3; Fig. 8 is a view showing the position of the horizontal movement cam when the film engaging pins are in the up position, and indicating in dotted lines the relative positions of the other cams; Fig. 9 is a view showing the vertical movement cam independent of the rest of the mechanism; Fig. 10 is a view showing the clamping cam being a sectional view taken as indicated by line 10—10 on Fig. 5, and Fig. 11 is a detailed sectional view taken as indicated by line 11—11 on Fig. 5 showing the horizontal movement cam in position to

cause the film engaging pins to be removed from the film.

The mechanism by the invention is adapted to be arranged in a case of any suitable design and construction and may be arranged to co-operate with a suitable shutter mechanism and with a suitable arrangement of lenses, etc. Further, the mechanism is reversible both as regards to arrangement, or position, and direction of operation.

For the sake of simplicity I am herein setting forth the mechanism independent of any particular casing, shutter mechanism, arrangement of lenses, etc., and am showing and describing the mechanism in only one particular position. It will be understood that the mechanism can be arranged in a casing in connection with a suitable shutter mechanism, etc., and it will be understood from the following description how it can be turned to any position and even inverted and yet operate properly.

Throughout the drawings numeral 10 designates a vertical wall, which in practice may form a portion of the front wall of the casing in which the mechanism is carried, and numeral 11 designates a vertical wall, arranged at right angles to, and to extend rearwardly from, the wall 10, which wall 11 may be a side wall of, or a partition in, the casing in which the mechanism is carried. The wall 10 is formed with a suitable aperture 12 in which is carried the aperture plate 13. The aperture plate 13 is formed with a suitably shaped aperture 14 the walls 15 of which extend through the aperture 12 and extend somewhat inwardly from the wall 10, as is clearly shown in Figs. 5 and 6 of the drawings. The film 17 is slidably carried between the film gate 18 and the gate carrier 19, so as to properly register with the aperture 14. Film gate 18 is formed with a suitable handle 20 and is removably held in place on the rear face of the gate carrier 19 by a spring clip 21. The gate carrier 19 is formed with an aperture 22 into which walls 15 of aperture plate 13 extend, thereby causing the film gate 18 to form a backing for that portion of the film which is in register with the aperture 14. The gate carrier 19 is pivotally connected at its lower end to the wall 10, by a pin 23, so that it can be moved or swung toward the wall 10 to cause the film to be clamped between the inner edges of

walls 15 and the film gate 18. The pin 23 extends through a suitable bracket 25^a, mounted on the back of wall 10, through bearings 24 formed on the gate carrier 19, 5 and into the wall 11, as clearly shown in the drawings. This means for clamping or holding the film 17 against movement is so that it can be positively held still at times when it is being exposed and is not being 10 moved by the film moving, or advancing, mechanism.

In order to operate the gate carrier 19 in synchronism with the film moving mechanism hereinafter described, or to clamp the 15 film 17 at suitable and proper times, a projection or arm 25 extends rearwardly from one side of the carrier 19 and has extending from it a pin 26^a which carries a roller 26 carried in a cam groove 27 formed in a disk 28. The disk 28 is mounted on a suitable 20 drive shaft 29. The drive shaft 29 is supported by a suitable ball-bearing 30, carried by the wall 11, and a suitable ball-bearing 31, carried at the outer end of a housing 32 which is mounted on, and which extends outwardly from, the wall 11, as clearly 25 shown in the drawings. Any suitable or ordinary drive may be provided for the drive shaft 29; for instance, a gear 33 may 30 be mounted on the outer end of the shaft to mesh with and be driven by a gear (not shown). The shaft 29 is held against longitudinal displacement, or movement, by a cone or annular protection 34 formed on it 35 to engage the balls of bearings 30, and a cone 35 screw threaded on its outer end to engage the balls of bearings 31. The cone 35 being screwed threaded on the shaft 29 is adjustable longitudinally relative to the 40 shaft thereby making it possible to set the shaft so that it will have only the necessary amount of longitudinal play.

The cam groove 27, in the disk 28, has two 45 portions, A and B, each of which is concentric with the disk 28 and shaft 29. The portion B of cam groove 27 is formed on a slightly greater radius than the section A and is somewhat longer than section A. The two sections A and B of the groove 27 are 50 connected so that the groove is continuous and to allow free passage of the roller 26 from one section to the other. When the disk 28 is in a position which causes the roller 26 to be in portion A, of the groove 55 27, the carrier 19 is in its out position which allows the film 17 to be moved between the aperture plate 13, and the film gate 18, while when the roller 26 is in portion B of cam groove 27 the carrier 19 is in its in position which causes the film 17 to be firmly 60 clamped between the aperture plate 13 and the film gate 18.

To move or advance the film 17, between the carrier 19 and film gate 18 at times when 65 it is not clamped or held between the film

gate 18 and aperture plate 13, two claws or pins 38 are carried by an arm 41. The pins 38 are of proper size and are so spaced as to properly fit the perforations or apertures provided in standard moving picture film, 70 and are arranged to extend through vertical slots 40 in the gate 18 in order to engage the film, as shown in the drawings. The pins 38 are carried at the ends of a cross arm 41 arranged at the end of guide 42. Guides 42 75 and 42^a extend from opposite sides of cam guide 47 and are slidably carried in apertures 43 and 44 in frame 45. The frame 45 is carried by suitable vertical guides, and is formed with a recess 46 between the portions in which the guide carrying apertures are formed in order to carry or receive the cam guide 47 which is formed with opposite faces 48 and 49 between which are carried the cam 50. The walls 80 and 81 of recess 85 46 form supports or guides for the cam guide 47 while the walls 82 and 83 of the recess 46 are spaced apart so that they will not interfere with the movement of cam guide 47 caused by cam 50. The walls or 90 faces 48 and 49 of the cam guide 47 are vertical and parallel with each other and are spaced apart to accurately receive the cam 50. The cam 50 is the horizontal movement cam and is mounted on the inner end of the 95 shaft 29, being secured thereon by a suitable screw 51. Further, the cam 50 is so shaped and is so mounted on the shaft 29 that when the shaft is rotated it causes movement of the pins 38 into engagement with the film 100 just before the frame 45 starts to move down, causes the pins to remain in engagement with the film during the downward movement of the frame, causes the pins to be withdrawn from the film when the frame 105 reaches the bottom of its movement, and causes the pins to remain withdrawn from the film during the upward movement of the frame. The cam 50 and the disk 28 are 110 mounted on the shaft 29 in such relative positions as to cause the pins and film gate to co-operate so that the film is released by the gate immediately after it is engaged by the pins, so that the film remains released and free to move while the pins are moved downwardly with frame 45, so that the film is 115 clamped or held after the frame has reached the bottom of its movement and just before the pins are withdrawn from it.

The up and down or vertical movement of 120 frame 45 above referred to is caused by a cam 55 mounted on shaft 29 between disk 28 and cam 50. The cam 55 is arranged to be between and to engage parallel horizontal guide surfaces 56 and 57 formed on frame 125 45 and it is so shaped and positioned on shaft 29 that it properly co-operates with the cam 50 and the cam groove 27. The throw of cam 55 is such as to cause the film 17 to be advanced a distance equal to 130

one picture each time shaft 39 makes a revolution.

It will be particularly noted in the drawings that the cams are all simple in construction and extremely compact in arrangement; and it will be readily understood how they can be shaped and proportioned so that the mechanism will operate easily, smoothly and effectively. The disk 28, cam 50, and cam 55 may be keyed to shaft 29 by a suitable key 90 and may be clamped or held together on the shaft 29 by the screw 51. In practice it is desirable to construct some of the parts so that they will be comparatively light. This may be very effectively done by forming holes and recesses in them at suitable places. For instance, the frame 45 may be formed with holes 95 and the cam 55 may be recessed at 96. Further it will be understood how the timing of the various movements or functions of the machine may be varied or changed by varying the shapes, sizes, or relative positions of the cams.

Any suitable means may be employed for guiding the frame 45 vertically. For instance, as shown in the drawings the frame may be formed with two suitably spaced vertical bores 60 which slidably receive two vertical guide rods 61. The guide rods are carried between horizontal disposed flanges 62 and 63 extending from a bracket 64 mounted on the inner face of wall 11 by screws 65.

Having herein set forth a preferred form of my invention I do not wish to limit myself to the particular details set forth but wish to reserve to myself any changes or variations that may appear to those skilled

in the art or that may fall within the scope 40 of the following claims.

Having described a preferred form of my invention, I claim:

1. A film moving mechanism comprising a vertically movable frame, a horizontally 45 movable film engaging member carried by the frame, a film clamping member, a rotating shaft, and three separate cams mounted on the shaft, one of the cams causing reciprocation of the frame, one causing reciprocation 50 of the film engaging member, and one causing operation of the film clamping member.

2. A film moving mechanism comprising, a vertically movable frame, a horizontally 55 movable film engaging member carried by the frame, a film clamping member, a rotating shaft, and three separate cams mounted on the shaft, one causing reciprocatory movement of the frame, one causing movement 60 of the film engaging member into engagement with the film at one end of the frame movement and out of engagement with the film at the other end of the frame movement, and the other positively holding the film clamping member out of engagement with the film when the film engaging member is in engagement with it and positively holding the film clamping member 65 in clamping engagement with the film when 70 the film engaging member is out of engagement with it.

In witness that I claim the foregoing I have hereunto subscribed my name this 7th day of May, 1920.

GEORGE A. MITCHELL.

Witness:

E. D. CAVENDER.
